UNITED STATES PATENT OFFICE

2,081,885

MECHANISM FOR SELECTIVELY REPRODUCING AND AUTOMATICALLY REPEATING SOUND RECORD MATERIAL

Arthur L. Runyan, New York, N. Y., assignor, by
means assignments, to Transaphon Corporation,
Newark, N. J., a corporation of New Jersey

Application August 8, 1935, Serial No. 35,383

46 Claims. (Cl. 274—15)

The invention relates to mechanism for selectively reproducing and automatically repeating sound record material.

The object of the present invention is to provide mechanism adapted for association with a numerical index for the selection of portions of a sound record and of reproducing and automatically repeating the same for educational purposes to facilitate the study of subjects requiring auditory perception, such as language, music, telegraphic code reception and the like.

A further object of the invention is to provide mechanism of this character adapted to enable the reproducer stylus or needle of a sound reproducing machine to be accurately positioned at any desired point on a sound record and accurately limited in its travel from such point in the spiral or feed groove of the record so that only the desired or selected portion of a sound record may be reproduced and automatically repeated according to the wishes of the operator.

A further object of the invention is to provide micrometer graduated manually operable adjusting or setting means corresponding with the number of the grooves of a sound record so that portions of a sound record in accordance with the indications on a numerical chart corresponding to the sound record may be easily selected and the mechanism adjusted so that the reproducer stylus will start on the record at the desired point indicated by the chart and will be automatically lifted from the record and returned to the selected initial starting point after having traversed the desired area of the record to automatically repeat all or the selected portion of the sound record as long as desired.

A further object of the invention is to provide repeat mechanism having means for returning the tone arm to its initial starting position which will be entirely inactive and have no effect on the tone arm while the same is in contact with the sound record so that no extra burden will be placed on the tone arm or the reproducer stylus and there will be no liability of causing increased wear or other injury to the sound record.

Another object of the invention is to provide repeat mechanism adapted to lift the tone arm and the stylus from the record before the means for swinging the tone arm to its initial or selected starting position is permitted to function so that the means for swinging the tone arm back to its initial position will not cause the reproducer stylus to exert an increased pressure on the walls of the feed groove of the record.

It is also an object of the invention to equip

the repeat mechanism with latch mechanism adapted when the tone arm is swung backwardly and returned to its initial starting position to positively hold the tone arm against swinging movement in either direction until the stylus is lowered to the sound record thereby insuring substantial accuracy in returning the tone arm to its initial position in each operation of the repeat mechanism.

A further object of the invention is to provide in addition to the manually operable micrometer adjusting or setting mechanism simple and effective means for permitting a final adjustment of the tone arm to compensate for variations in the starting points of sound records so that adjustments made from a chart may correspond with the material on sound records irrespective of variations in the starting points of the material on such records.

A further object of the invention is to provide a repeat mechanism capable of use independently of the automatic means for continuously repeating all or portions of a sound record, and adapted to be adjusted to position the reproducing needle or stylus for starting the reproduction at the desired point on a sound record and capable when the desired amount of the sound record has been reproduced of being manually operated to stop the reproduction and cause the tone arm and the reproducer stylus to be mechanically returned by the mechanism of the reproducer to its initial starting position and the needle to be lowered at such point upon the sound record for repeating the previously reproduced area of the sound record, thus enabling the reproducer needle to be set for starting sound reproduction at the desired point on the sound record and the sound reproduction to be manually stopped at the desired point with the operation of the repeat mechanism otherwise automatic.

With these and other objects in view, the invention consists in the construction and novel combination and arrangement of parts herein-after fully described, illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:

Fig. 11 is a detail view of the upper right hand corner portion of a numerically indexed sheet.

Fig. 12 is an edge view of a plurality of numerically indexed sheets arranged in a binder.

Fig. 13 is a diagrammatic view of the motor circuit.

Fig. 14 is a sectional view on the line 14—14 of Fig. 5.

Fig. 15 is a horizontal sectional view on the line 15—15 of Fig. 14.

Fig. 16 is a horizontal sectional view on the line 16—16 of Fig. 3.

Fig. 17 is a detail view partly in section illustrating the manner of mounting the pivoted mercury switch shown in Figs. 4, 5, and 6.

In the accompanying drawings in which is illustrated the preferred embodiments of the invention, 1 designates a cabinet or casing of a sound reproducing machine which may be of any desired construction as the present invention is applicable to various types of sound reproducing machines such as an ordinary phonograph or a sound reproducing means having an amplifying unit and equipped with a crystal or magnetic pick-up. The sound reproducing machine includes a turntable 2 actuated by an electric motor 2a and adapted to receive a sound record 3 having the usual feed grooves 4 which are engaged in the ordinary manner by a stylus 5 of the tone arm 6, whereby the rotation of the sound record through its spiral feed groove carries the tone arm inwardly over the record in the usual manner for reproducing the sound of the record.

The term "grooves" of the sound record refers to the number of convolutions or the pitch to which the spirally grooved record is cut. As the sound reproducing machine may be of any desired construction and as the present invention is applicable to all types of sound reproducing machines detailed illustration and description thereof are deemed unnecessary. It

will be understood that the term "tone arm" comprehends any form of horizontally swinging arm for carrying sound reproducing means.

The tone arm 6 which may be constructed of any suitable material is hollow and in the forms of the invention illustrated in the accompanying drawings is open at the bottom and composed of spaced side and end walls and a connecting top portion and it is pivotally connected at a point intermediate of its ends by a transverse pivot 7 to a supporting arm or bar 8 extending from and preferably formed integral with a sleeve 9 mounted for pivotal or swinging movement on an upright spindle 10. The spindle 10 is suitably secured at its lower end to a tiltable support 11 which is oscillated vertically by means hereinafter described for raising and lowering the tone arm and the reproducer stylus to lift the stylus from the sound record and to return the stylus to the record. When the tone arm is in its lowered position the spindle 10 is substantially vertical and the supporting arm 8 is disposed at a slight inclination and extends upwardly and outwardly from the sleeve 9 as clearly illustrated in Figs. 2 and 4 of the drawings.

While two forms of the invention are illustrated in the accompanying drawings as herein-after fully explained these forms differ from each other principally in the means for actuating the tiltable support for raising and lowering the tone arm. The parts of the two forms of the invention which are identical have the same reference character and a single specific description of such parts is deemed ample.

The tone arm 6 is provided in its top adjacent its inner end with an opening 12 through which the upper end of the spindle 10 projects and the outer end of the supporting arm 8 is provided with an enlargement 13 in which is threaded for vertical adjustment a tone arm lifting screw 14 which engages the tone arm and lifts the same from the record when the support 11 is tilted from the approximately horizontal position illustrated in Figs. 2 and 4 of the drawings to the inclined position shown in Figs. 3 and 5. When the tone arm is lowered to the sound record and is in the position illustrated in Figs. 2 and 4 of the drawings the top portion of the tone arm clears the lifting screw and floats free of the same to enable the reproducer stylus to engage the grooves of the sound record in the usual manner. The adjustment of the lifting screw 14 of the arm 8 is adapted to enable the tone arm to be adjusted to enable its reproducer stylus to operatively engage records of different thicknesses and the adjustment of the screw 14 will enable the proper clearance between the screw and the tone arm to be provided for this purpose.

The supporting arm 8 is provided at the pivot 7 with hollow spacing lugs 15 through which the pivot 7 passes and which spaces the sides of the tone arm 6 from the supporting arm 8 as clearly shown in Fig. 1 of the drawings. The lower end 16 of the spindle is threaded for the reception of a nut 17 and is secured to a bearing bracket 18 which is arranged upon the upper face of the tiltable support 11. Also the threaded lower end of the spindle 10 and the nut 17 provide convenient means for securing a lower bearing bracket 19 to the tiltable support. The tiltable support may conveniently consist of a substantially oblong plate provided with upstanding reinforcing side flanges 20 and arranged in a substantially oblong opening 21 in 75

5 a supporting frame 22 which may be of any desired construction. In practice the supporting frame 22 will be removably mounted in the cabinet 1 as clearly illustrated in Fig. 1 of the drawings and when the platform is in a horizontal position the front end 23 rests upon and is supported by the adjacent portion of the supporting frame 22. The tiltable support which constitutes a platform is pivotally mounted on 10 the supporting frame at opposite sides by suitable pivots 24 which are mounted in suitable ears 25 of the supporting frame and which pierce the side flanges 20 of the tiltable support but the tiltable support may be pivotally mounted in 15 any other desired manner as will be readily understood.

10 The bearing bracket 18 which is fixed to the central portion of the tiltable platform supports a worm actuated toothed segment 26 which is 20 loose on the spindle for rotary adjustment by a worm 27 to change the position of a normally stationary adjustable contact carrying bracket 28. The worm actuated segment 26 constitutes a support which is mounted for horizontal rotary 25 or oscillatory movement on a vertical axis. The segment 26 which is provided with an arcuate series of teeth 29 to mesh with the worm 27 rests upon the upper face of the bearing bracket 18 and the bearing bracket 18 is provided at its rear 30 end with transversely aligned bearings 30 in which is mounted a worm shaft 31 having the worm 27 fixed to it. The worm shaft 31 extends laterally beyond one side of the tiltable support 11 and has mounted on it a micrometer 35 graduated drum 32 for the adjustment of the worm actuated segment 26. When the drum is rotated rotary movement will be imparted to the worm actuated segment 26 through the worm 27 and after adjustment the worm will form a lock 40 to maintain the worm actuated segment 26 and the contact carrying bracket 28 in their adjustment.

45 The micrometer graduated drum is provided at its outer end with a milled flange 33 to facilitate manual operation and it is provided with a spiral groove 34 which is engaged by projections 35 of an indicator 36. The spiral face portion 37 of the drum between the grooves is provided with numbered graduations 38 corresponding 50 with the grooves of the sound record 3 so that each groove of the sound record corresponds with a graduation of the drum 32. The spiral disposition of the face portion 37 provides a continuous graduated portion of the drum face 55 of sufficient length to enable amply spaced graduations on the drum to correspond to the closely arranged grooves of the sound record 3. In practice a 12 inch sound record will have approximately 400 grooves. The number of 60 grooves of a 12 inch sound record may vary but 400 is generally the maximum number of grooves of such a record and the particular construction of the micrometer graduated drum will enable an excess of 400 graduations of the drum to be 65 spaced a sufficient distance apart to be readily viewed so that the drum may be manually operated with precision for positioning the normally fixed adjustable contact carrying bracket at the desired point as one of the determining factors 70 for enabling the desired amount of the sound record material to be automatically and continuously repeated as hereinafter fully explained.

75 The indicator 36 which is curved to conform to the cylindrical configuration of the drum fits

flat against the graduated portion of the same and preferably consists of a plate provided between its ends with a transverse sleeve 39 which is slidably mounted on a fixed transverse guide rod 40. The projections 35 which engage the spiral groove at opposite sides of the spiral graduated face portion 37 of the drum may consist of pins or any other suitable means and the indicator which is slidably laterally on the transverse guide rod 40 when the drum is rotated is 10 provided with a window 41 and it has an indicating member or arrow 42 consisting of an integral projecting portion of the indicator and extending inwardly at one side of the window and tapered to a point which cooperates with the graduations 15 of the drum. The guide rod 40 which is of a length to extend across the spiral graduated portion 37 of the drum is carried by a supporting bracket 43 which may be secured to the tiltable support in any desired manner. The micrometer 20 graduated drum 32 is preferably located at the left hand side of the tiltable support looking toward the tone arm in Fig. 1 of the drawings but the arrangement may be changed if desired, and the lower peripheral portion of the drum 32 extends below the upper face of the tiltable support and the top of the supporting frame 22 is provided with an opening 44 to receive the lower portion of the drum.

30 A washer 45 which constitutes a spacing member is arranged on the spindle 10 and is interposed between the worm actuated segment 26 and an upper bearing bracket 46 provided with an opening 47 to receive the spindle 10 and loosely mounted on the same for free rotative movement incident to the swinging movement of the tone arm which is adjustably positioned by the means hereinafter described with relation to the upper bearing bracket 46. The bearing bracket 46 provides a support mounted on a vertical axis 40 for horizontal rotary or swinging movement to permit actuation of the tone arm by the sound record. The upper bearing bracket 46 has fixed to it a movable contact carrying bracket 48 which swings toward and from the fixed contact carrying bracket as the tone arm is carried over the sound record in reproducing sounds therefrom and when the tone arm is raised from the sound record and is swung outwardly to return it to its initial starting position. The upper bearing bracket is provided at opposite sides with transversely aligned bearings 49 in which is mounted a transversely disposed worm shaft 50. A worm 51 which is fixed to the worm shaft 50 meshes with a worm actuated segment 52 provided with an arcuate series of teeth 53 which mesh with the worm 51 as clearly illustrated in Fig. 1 of the drawings. The worm actuated segment 52 is provided with a central opening 54 through which passes the spindle 10 and which also receives a sleeve 55.

55 The sleeve 55 projects upwardly from the worm actuated segment 52 and extends into the sleeve 9 of the supporting arm 8. The sleeve 9 of the supporting arm 8 is arranged on the extended portion of the sleeve 55 and is supported upon the upper face of the worm actuated segment 52. The supporting arm 8 and the tone arm 6 are connected with the worm actuated segment 52 and the rotary movement or adjustment of the segment 52 by the rotary movement of the worm 51 adjusts the tone arm and arranges the same in the desired position with relation to the bearing bracket 46 so that when the bearing bracket is carried to its initial or starting posi- 70

tion the tone arm will be positioned at the desired point on the sound record for starting the reproduction of the desired portion of the same.

The worm 51 is pinned or otherwise fixed to the worm shaft 50 which extends laterally from the right hand side of the laterally tiltable support in Fig. 1 of the drawings and it has fixedly mounted on it a manually operable micrometer graduated drum 56 constructed the same as the drum 32. The drum 56 is provided at the outer end with a milled flange 57 and it has a spiral groove 58 defining a spirally arranged surface 59 provided with numbered graduations 60 corresponding to the grooves of a sound record. A laterally slidably indicator 61 cooperates with the graduations 60 of the spirally disposed peripheral surface of the drum and is of the same construction as the indicator 36 heretofore described.

20 The indicator 61 which may be constructed of any suitable material is provided with a sleeve 62 and it has projections 63 located at opposite sides of it and formed by pins or other suitable means. The projections 63 extend into the 25 spiral groove 58 and cause the indicator to move laterally on a transverse guide rod 64 when the drum is manually rotated. The transverse guide rod 64 which extends across the face of the drum in spaced relation thereto is mounted at its 30 inner end in a bracket 65 which is fixed to the upper bearing bracket 46. The slide 61 is provided at the spirally graduated portion 59 with a window 66 and it has an indicating member or arrow 67 preferably formed by an integral 35 tapered portion of the slide. The arrow 67 projects inwardly with respect to the window and is located at the graduations 58 of the drum. The spiral arrangement of the graduated portion of the face of the drum is of sufficient length to 40 enable the graduations to be readily seen and to be from 0 to the required number necessary to correspond to any size record or pitch to which the grooved record is cut. As before explained the maximum number of convolutions or grooves 45 of a 12 inch record is approximately 400 and the graduations of the drum 56 are numbered from 0 to 400 and are continued slightly in excess of the latter, as clearly illustrated in Fig. 1 of the drawings.

50 If a 12 inch record was cut to 650 pitch per 4 inches or less than 400 pitch per 4 inches then the graduated drum would not correspond but the chart would indicate the approximate number to dial to lower needle to the position on 55 record and chart would further show the position to dial repeat drum for repetition.

This will be ample for the standard 12 inch records but it will be readily understood that the spiral graduated portions of the drums 32 and 60 66 may be made of any desired length to provide ample space for the graduations to correspond to the pitch to which any desired size of record may be cut.

When the micrometer graduated drum 32 is 65 turned to a given number in register with the arrow 42 in the window of the indicator 36 above the face of the drum 32 it will place the reproducer needle in a selected position above the related record groove of the sound record 3 on 70 the turntable. By means of the worm 51 of the segment 52 the tone arm is actuated at a speed less than that of the drum. The other micrometer graduated drum 56 when turned to any given number from a zero position advances 75 the contact carrying bracket 28 ahead of the

contact carrying bracket 48 and spaces it from the said contact carrying bracket 48 and when the reproducer needle is lowered into the record groove the turntable must make the number of revolutions indicated in the window 66 of the slide 61 of the micrometer graduated drum 56 before the contact carrying bracket 48 reaches the contact carrying bracket 28 and closes a motor circuit 68 for lifting the tone arm and the reproducer needle from the sound record 10 as hereinafter fully explained.

When the tone arm is lifted from the sound record by the tilting of the support 11 and is swung outwardly with respect to the record to the selected initial or starting position it is while elevated locked in such initial position by a latch 69 pivoted at 70 to a fixed bracket 71 and engageable with a keeper recess 72 of a latch engaged member 73 rigid with and carried by the upper bearing bracket 46. The fixed bracket 20 71 is mounted on the supporting frame 22 and may be secured to the same in any desired manner. As illustrated in the accompanying drawings it is arranged at the front of the supporting frame and it extends upwardly and inwardly over the front portion of the tiltable support. The pivot 70 of the latch 69 is located adjacent one end of the latch and the bracket is provided at opposite sides of the vertical plane of the pivot 70 with stops 74 and 75 which limit the swinging movement of the latch. The latch engaged member 73 may be connected with the upper bearing member 46 by means of the contact carrying bracket 48 or by any other suitable means. It is provided at its front or outer portion with an arcuate flange 76 arranged to receive the latch 69 when the front portion of the tiltable support 11 is elevated and the latch rides on the flange 76 during the return movement of the tone arm and drops into the keeper recess 72 as soon as the tone arm reaches its selected initial position.

The flange 76 is provided at the outer side of the keeper recess 72 with a projecting portion 77 which forms a stop shoulder for accurately limiting the movement of the latch engaged member and the tone arm in one direction for insuring the return of the tone arm to its precise selected initial position. In Fig. 7 of the drawings the latch 69 is shown supported by the flange 76, the tone arm being elevated as illustrated in Fig. 5 of the drawings. In Fig. 8 the latch 69 is shown in engagement with the keeper notch 72 for squaring the tone arm with relation to the sound record so that the reproducer needle 5 will be lowered to the precise point selected for starting the playing or reproduction of the sound record.

In Fig. 9 of the drawings the latch 69 is shown 60 clear of the keeper recess 72, the tone arm having been lowered to engage the reproducer needle with the sound record 3 as illustrated in Fig. 4 of the drawings.

The tiltable support 11 is adapted to be locked in its tilted position with the latch 69 in engagement with the keeper recess 72 by means of a manually operable locking lever 78 pivoted at 79 in a bracket 80 fixed to the rear portion of the supporting frame 22. The pivot 79 is located adjacent to one end of the manually operable locking lever 78 to form a toe or engaging portion 81 which is adapted to be swung downwardly from the full line position shown in Fig. 5 to the dotted line position illustrated in the 75

said figure for locking the outer or rear portion of the tilttable support in its lowered position.

This locking of the support 11 in its tilted position will maintain the same rigidly in such position while the tone arm is held rigidly against swinging movement by the engagement of the latch 69 with the keeper recess 72. This will facilitate accurate adjustment of the tone arm and the adjustable contact carrying bracket 10 although such adjustment may of course be made without locking the tilttable support. Also the locking lever is adapted to be manually operated for lifting the inner or front portion of the tilttable support 11 and the tone arm carried there- 15 by and for causing a manual operation of the mechanical means hereinafter described, for returning the tone arm to its initial position without closing the motor circuit 68 and independently of the same so that under certain conditions a motor and motor circuit and contact carrying brackets may be omitted to provide an inexpensive manually operable repeat mechanism for sound reproducing machines.

In addition to the adjustment or positioning 25 of the tone arm afforded by the micrometer graduated drum and the connections between the same and the worm actuated segment 52 final adjustment means is provided to permit the tone arm to be adjusted to compensate for variations 30 which may occur in the starting point of a sound record so that the tone arm may be adjusted with relation to any particular sound record and the reproducer needle of the tone arm will when lowered to the sound record correspond exactly 35 with the numbered graduations of the drum 56.

The upper worm actuated segment 52 is provided at the front or inner portion with lugs 82 and 83 spaced apart to receive a depending extension 84 of the supporting arm 8. The extension 84 is preferably in the form of a lobe, as clearly illustrated in Fig. 5 of the drawings, and the arm 83 is provided at the outer side with a laterally extending tubular barrel 85 closed at the outer end and containing spring means for urging the supporting arm inwardly with respect to the lug 83. The spring means preferably consists of a plunger 86 and a coil spring 87. The plunger extends through the lug 83 and the other lug is provided with an adjusting screw 88 having a threaded engagement with the lug 82. The lobe 84 of the supporting arm 8 is preferably provided at each of its side faces with an indentation 89 to receive either the inner end of the adjusting screw 88 or the engaging end of the plunger 86. The adjusting screw 88 is adapted to move the supporting arm away from the lug 82 and towards the lug 83, the spring actuated plunger 86 yielding to the action of the screw. The screw is also adapted to be adjusted to permit the spring actuated plunger to move the supporting arm away from the lug 83 and towards the lug 82. By the means of the screw and the spring actuated plunger the supporting arm 48 which carries the tone arm may be adjusted from the central position in the space between the lugs 82 and 83 to either of the said lugs and a relatively small adjustment at the inner or pivoted end of the supporting arm 8 will afford a relatively large adjustment of the reproducer needle 70 at the outer end of the tone arm sufficient to amply compensate for variations in the starting point of sound records.

The upper bearing bracket 46 with which the tone arm is adjustably connected is provided at 75 opposite sides with laterally aligned shoulders 90

arranged to be engaged by side portions 91 of a forked lever 92 fulcrumed on the depending bracket 19 at a point intermediate of its ends by a transverse pivot 93 and having a lower arm 94 arranged to be carried into engagement with a stop 95. The lever 92 is reinforced by side flanges 92a and the pivot 93 passes through the side flanges 92a and the sides of the bracket 19 which is approximately U-shaped in horizontal section. The stop 95 preferably consists of a bracket mounted on the supporting frame 22 at the bottom thereof and arranged in the path of movement of the lower arm 94 and adapted after being engaged by the arm 94 to hold the same against further movement whereby the upper tilting of the inner or front portion of the support 11 causes a relative movement of the upper arm of the lever 92 and an engagement of the side portions 91 of the fork of the lever 92 with the side shoulders 90 of the upper bearing bracket. One of the sides of the forked portion of the lever 92 engages one of the shoulders 90 and produces a partial rotary movement of the upper bearing bracket and a swinging movement of the tone arm and returns the same to its selected starting position. The other side of the forked portion of the lever 92 engages with the other shoulder at the completion of the swinging movement of the tone arm and the upper bearing bracket is squared or returned to its initial position and is locked in such position by the latch 69 until released from such locked position by the downward movement of the inner portion of the tilttable support.

Instead of employing a bracket 95 any other suitable means may be provided for holding the lower arm 94 of the forked lever for causing an engagement of the same with the side shoulders of the upper bearing bracket. Also while the side shoulders 90 of the upper bearing bracket 46 are illustrated in the drawings as formed by integral laterally extending portions of the said bearing bracket 46 any other suitable means may be employed for providing the side shoulders to cooperate with the forked lever for returning the bearing bracket and squaring or centering the same at the completion of such return movement.

The front elevated portion of the tilttable support when free to move is moved downwardly by a coil spring 96 which lowers the tone arm and the reproducer needle to the sound record. In Figs. 2 and 3 of the drawings an electric motor 97 is employed for furnishing the energy for tilting the support 11 to elevate the inner or front portion thereof and raise the tone arm and the reproducer needle from the sound record and the spring 96 which is secured at one end to the frame 22 is connected at its other end to an arm 97a fixed to and extending downwardly from the bracket 19 and carrying at its lower end a roller 98 which cooperates with a rotary cam 99 actuated by the electric motor 97. The roller 98 which is preferably mounted in a forked or bifurcated portion of the arm 97a is held against the periphery of the cam 99 by the spring 96 and when the cam is rotated and carried from the position illustrated in Fig. 2 of the drawings to that shown in Fig. 3 the support 11 is tilted from the horizontal position illustrated in Fig. 2 to the inclined position shown in Fig. 3.

When the cam 99 is rotated from the position shown in Fig. 3 to that illustrated in Fig. 2 the spring brings the tilttable support from the tilted

position shown in Fig. 3 to the horizontal position illustrated in Fig. 2, the cam controlling the action of the spring in moving the tiltable support from its inclined position to its normal horizontal position. The cam 99 is mounted on a cam shaft 100 which is connected with the motor shaft by suitable speed reducing gearing (not shown).

The cam shaft also carries a switch controlling cam 101 which is engaged at its periphery by a roller 102 of a mercury switch 103 pivotally mounted at 104 on the main frame 22 at the bottom thereof and engaged by a spring 105 which maintains the roller 102 in contact with the periphery of the switch controlling cam 101. The switch controlling cam 101 is provided with a cut-out 106 of substantially segmental form presenting a concave peripheral edge to the roller 102 and permitting the spring 105 to tilt the mercury switch and cause the mercury to flow to the end remote from the contacts 107 for opening the motor circuit 68. The mercury switch is arranged in parallel with contacts 108 and 109 mounted on the contact carrying brackets 28 and 48 and operates through the cam 101 to maintain the motor circuit closed until after the complete separation of the contacts 108 and 109 when the tone arm is swung outwardly with respect to the sound record to return the tone arm to its selected starting position.

After the tone arm has been returned to its starting position it is lowered to the sound record through the operation of the spring 96 and the cam 99, the motor circuit being opened and the motor stopped when the cut-out 106 of the cam is carried to the roller 102 of the mercury switch and the latter tilted to carry the mercury thereof from the contacts 107 to the opposite end of the mercury switch. The cut-out 106 permits the spring 105 to swing the contact carrying end of the mercury switch upwardly a sufficient distance to arrange the mercury switch in an inclined position opposite to that illustrated in Figs. 2 and 3 of the drawings. The contacts 108 and 109 are insulated from the contact carrying brackets 28 and 48 and the arrangement of the said contacts in parallel with the mercury switch is indicated diagrammatically in the motor circuit in Fig. 13 of the drawings.

In Figs. 4 and 5 of the drawings is illustrated another form of the invention in which a solenoid 110 is employed instead of an electric motor for supplying rotary motion. The solenoid which is preferably arranged in a vertical position is provided with a vertically movable core 111 and constitutes a motor for furnishing reciprocatory motion for tilting the support 11 from the horizontal position illustrated in Fig. 4 of the drawings to the inclined position shown in Fig. 5. The core 111 carries a plunger extension 112 which when elevated by the closing of the motor circuit flexes a bowed spring 113 and stores up sufficient energy in the same to tilt the support 11.

The bowed spring is secured to the front end of the support 11 at the lower face thereof and it extends beyond the supporting frame and terminates at a point above the plunger extension 112 of the core 111. The tilting movement of the support 11 under the influence of the spring 113 is controlled by a dashpot 114 of the ordinary construction. The dashpot 114 which is arranged vertically is pivotally mounted at its lower end at 115 in the supporting frame at the

bottom thereof and its plunger 116 is pivotally connected at the upper end at 117 to the outer portion of the tiltable support 11 at the lower face of the same. Also a coiled spring 118 is preferably disposed on the plunger 116 interposed between the cylinder of the dashpot and a head 119 formed on the upper end of the plunger 116 for the pivotal connection between the plunger and the tiltable support. When the spring 113 is flexed by the closing of the motor or solenoid circuit the inner portion of the platform is elevated with a controlled motion and the forked lever 92 operates in the manner heretofore described to return the tone arm and the reproducer needle to the selected initial position. The contact carrying arms 28^a and 48^a of the form of the invention illustrated in Figs. 4-6, inclusive, carry contacts 120 and 121 and the bracket 48^a also carries a mercury switch 122 arranged in parallel with the contacts 120 and 121 of the solenoid circuit and pivotally mounted at 123 in a yoke 124 secured to an arm 125 extending laterally from the contact carrying bracket 48^a.

The solenoid circuit is the same as the motor circuit with the exception of the solenoid being substituted for the motor. Detailed illustration of the solenoid circuit is deemed unnecessary. The pivotal connection between the mercury switch and the yoke is formed by spaced pivots 123 passing through gears 126 of a lever 127. The lever 127 is fulcrumed intermediate its ends and its inner arm carries a spring clip 128 for holding the mercury switch 122 and the outer arm is engaged by a switch controlling member 129 having an attaching flange 120^a secured to the supporting frame. The switch controlling member 129 consists of an approximately horizontal plate normally located above the front arm 130 of the lever 127 and when the inner portion of the tiltable support is elevated to the position illustrated in Fig. 5 of the drawings the lever 127 is swung on its pivotal connection 123 and the mercury switch is tilted to close the solenoid circuit and will maintain the solenoid circuit closed as a solenoid circuit after the separation of the contacts 120 and 121 and prevent arcing of the same. The mercury switch 122 maintains the solenoid circuit closed until the contact carrying arm 48^a and the tone arm are returned to their initial or starting position. This movement also carries the arm 130 of the lever 127 beyond the switch controlling member 129 and permits the mercury switch to tilt automatically from the inclined position shown in Fig. 5 of the drawings to the oppositely inclined position illustrated in Fig. 4 for causing the mercury of the switch to leave the contacts 131 of the mercury switch and open the solenoid circuit and deenergize the solenoid.

The springs 113 and 116 insure the return of the tiltable platform to its normal horizontal position illustrated in Fig. 4 of the drawings.

The operation of the repeat mechanism of the form of the invention illustrated in Figs. 4 to 6, inclusive, of the drawings is the same as that of the form of the invention illustrated in Figs. 2 and 3 of the drawings and the movement of the tiltable support 11 is controlled to permit a smooth and gentle operation of the mechanism in raising the tone arm from the sound record and in swinging it horizontally to its selected initial position and in lowering the tone arm and the reproducer needle to the sound record. The micrometer graduated drum at the right hand side of Fig. 1 of the drawings is set with the

arrow of the indicator at 0 for starting the playing of the sound record 3 at the beginning thereof and the arrow of the indicator of the left hand micrometer graduated drum in Fig. 1 of the drawings is set at 400. This setting will cause the entire sound record to be played and continuously reproduced. The micrometer graduated drums may be operated to set the indicator at any point between 0 and 400 on each drum so that any portion of the sound record 3 may be played and automatically repeated continuously. In practice a numbered index sheet 132 is designed to be provided for each sound record and these may be conveniently bound in a loose leaf binder as indicated at 133.

The upper right hand corner of one of the sheets is shown in Fig. 11 on an enlarged scale. These numbered index sheets which correspond with the graduations of the micrometer drums enable the tone arm to be adjusted for starting the playing of the record at the desired point and the adjustment of the normally stationary contact controlled by the micrometer graduated drum 32 will enable the desired portion of the sound record to be played. Also if desired the normally stationary adjustable contact which is controlled by the micrometer drum 32 may be set at the limit of its adjustment and only the tone arm adjusted to select the desired starting point on the record. The record may then be played and the tone arm may be raised and the played portion repeated by operating the locking lever 18 which when swung from the position shown in full lines in either Fig. 2 or Fig. 4 of the drawings to the dotted line position illustrated in the said figures will elevate the front portion of the tiltable platform and lift the tone arm from its association with the sound track of sound record and return the tone arm to its selected starting position. The locking lever may then be operated to release tiltable support and permit the tone arm to be lowered to the sound record for repeating the previously played portion of the record. In this manner the repeat mechanism may be manually controlled without the electrical means for the automatic operation of the repeat mechanism.

In order to enable the micrometer graduated drum to be set in the proper position with relation to the worms the outer end portion of each of the worm shafts is split at 134 and is provided with a bore 135 threaded at its inner portion 136 and tapered at 137 at its outer split portion. The threaded portion of the bore is located beyond the split portion and is adapted to be engaged by the threaded portion 138 of a screw 139 which is provided beyond the threaded portion 138 with a tapered portion 140 located at the head end of the screw and adapted to engage the walls of the tapered portion 137 of the bore of the worm shaft for expanding the same within a hub 141 of the micrometer graduated drum. In practice the micrometer graduated drum which may be constructed of any suitable material is provided at its ends with heads having suitable bearings for the worm shaft, the bearings being preferably in the form of hubs or enlargements but any other suitable construction may of course be employed.

Instead of employing numerals for designating the different graduations of the micrometer graduated drum any other desired characters or symbols whether American or foreign may be provided for this purpose as well as raised characters for the blind to enable the blind to

feel the position of the micrometer in relation to arrow in window.

In practice the numerically indexed charts 132 will be provided with numerical designations 142 associated with the subject matter of the charts 5 for designating the settings of the repeat mechanism. The numerical designations preferably consist of the letter R and a number. These may be arranged wherever required or desired to show where the micrometer graduated 10 drum 36 of the repeat mechanism is to be set for repeating the selected subject matter of the sound record related to the subject matter of the chart. The numbers on the chart for positioning the tone arm will designate the starting point for any 15 selected area of a sound record so that the chart will have starting and finishing numbers of any section of the sound record desired for reproduction and repetition, the numbers on the chart being related to both drums as well as the convolutions or grooves of the sound record for all 20 or any portion of the record selected for reproduction and repetition.

What is claimed is:

1. In mechanism for reproducing and repeating the whole or any selected portion of a sound record, a sound reproducer adapted for coaction with a sound record, means for actuating the sound record, a support carrying the reproducer and movable downwardly to operatively engage 30 the reproducer with the selected portions of the record and upwardly to withdraw the reproducer therefrom, said reproducer being mounted for inward and outward movement with respect to the sound record, and a lever carried by the support and mounted for pivotal movement with respect to the same to impart movement to the reproducer to return the reproducer to its starting position when the reproducer is lifted from the record, and means for effecting relative movement 35 between the lever and the support when the latter is moved to lift the reproducer from the record.

2. In mechanism for reproducing and repeating the whole or any selected portion of a sound record, a sound reproducer adapted for coaction with a sound record, means for actuating the record, a support mounted to tilt on a horizontal axis to operatively engage the reproducer with selected portions of the record and to withdraw 50 the reproducer therefrom, means for mounting the sound reproducer on said support for inward and outward movement with respect to the sound record, a pivotally mounted lever carried by the support and arranged to impart movement to the 55 reproducer to return the reproducer to its starting position when the support is tilted to lift the reproducer from the record, and a stop engageable with said lever for causing relative movement between the lever and the pivotal support to 60 actuate the reproducer in returning the same to the starting point.

3. In mechanism for reproducing and repeating the whole or any selected portion of a sound record, a support tiltable on a horizontal axis, 65 a sound reproducer adapted for coaction with a sound record and carried by the support in the tilting movements thereof to operatively engage the reproducer with the sound record and to lift the reproducer therefrom, means actuated by the 70 tilting movement of the support for returning the reproducer to its starting position, and a manually operable lever arranged to tilt the support for lifting the reproducer from the sound record, said lever being movable to a position to form a 75

- stop for holding the reproducer in an elevated position.
4. In mechanism for reproducing and repeating the whole or any selected portion of a sound record, including a support movable upwardly and downwardly, a sound reproducer including a horizontally swinging tone arm carried by and swingable with respect to the support and adapted to be operatively engaged with a sound record and to be withdrawn therefrom by the downward and upward movement of the support, and means operative only when the tone arm is elevated for returning the tone arm to its starting position, including a member mounted on the support for relative movement to swing the tone arm outwardly, and means for causing such relative movement between said member and the support when the latter is elevated.
5. In mechanism for reproducing and repeating the whole or any selected portion of a sound record, a tiltable support, a bracket element mounted for horizontal pivotal movement on the support, a sound reproducer adapted for cooperation with a sound record and including a horizontally swinging tone arm mounted on and movable with the bracket element and adapted to be operatively engaged with a sound record and to be withdrawn therefrom by the tilting movement of the support, and means engageable with the bracket element for actuating the same to swing the tone arm to return the same to its starting position when the support is tilted to lift the tone arm from the record.
6. In mechanism for reproducing and repeating the whole or any selected portion of a sound record, a tiltable support, a bracket element mounted for horizontal pivotal movement on the support and carried by the latter in the tilting movement thereof, a sound reproducer adapted for cooperation with a sound record and including a horizontally swinging tone arm mounted on and movable with the bracket element and adapted to be operatively engaged with a sound record and to be withdrawn therefrom by the tilting movement of the support, means for adjustably connecting the tone arm with the bracket element for arranging the starting position of the tone arm at any point on a sound record, and means carried by the support and movable with relation to the same for swinging the bracket element to a predetermined position and the tone arm to its selected starting position when the tone arm is lifted from the record by the tilting movement of the support.
7. In mechanism for reproducing and repeating the whole or any selected portion of a sound record, a tiltable support, a bracket element mounted for horizontal pivotal movement on the support, a sound reproducer adapted for cooperation with a sound record and including a horizontally swinging tone arm mounted on and movable with the bracket element and adapted to be operatively engaged with a sound record and to be withdrawn therefrom by the tilting movement of the support, means for adjustably connecting the tone arm with the bracket element for arranging the starting position of the tone arm at any point on a sound record, and means including a lever mounted for pivotal movement on the support and actuated by the latter to engage the bracket element and swing the tone arm to its starting position when the tone arm is lifted from the record by the tilting of the support.
8. In mechanism for reproducing and repeating the whole or any selected portion of a sound record, a tiltable support, a bracket element mounted for horizontal pivotal movement on the support and carried by the same in the tilting movement thereof, a sound reproducer adapted for cooperation with a sound record and including a horizontally swinging tone arm mounted on and movable with the bracket element and adapted to be operatively engaged with a sound record and to be withdrawn therefrom by the tilting movement of the support, means for adjustably connecting the tone arm with the bracket element for arranging the starting position of the tone arm at any point on a sound record, means carried by the support and movable with relation to the same for swinging the bracket element to a predetermined position and the tone arm to its selected starting position when the tone arm is lifted from the record by the tilting movement of the support, and means for holding the tone arm in its starting position until the tone arm is lowered to the record, the latter means comprising a latch mounted on a fixed support, and a latch engaging member connected with the bracket element and arranged to be engaged by the latch when the tone arm is elevated and has returned to its starting position.
9. In mechanism for reproducing and repeating the whole or any selected portion of a sound record, a tiltable support, a bracket element mounted for horizontal pivotal movement on the support and carried by the same in the tilting movement thereof, a sound reproducer adapted for cooperation with a sound record and including a horizontally swinging tone arm mounted on and movable with the bracket element and adapted to be operatively engaged with a sound record and to be withdrawn therefrom by the tilting movement of the support, means for swinging the bracket element to a predetermined position when the support is elevated, means for adjustably connecting the tone arm with the bracket element for adjusting the tone arm with relation to the said means for arranging the starting position of the tone arm at any point on a sound record, a latch engaging member connected with the bracket element and movable upwardly and downwardly with the tilting platform and provided with a substantially arcuate portion having a keeper, and a latch mounted on a fixed support and arranged to ride on the said arcuate portion when the tone arm is elevated and adapted to engage the keeper when the tone arm is returned to its starting position whereby the tone arm will be locked in such position until the same is lowered to the sound record.
10. In mechanism for reproducing and repeating the whole or any selected portion of a sound record, a tiltable support, a sound reproducer including a horizontally swinging tone arm carried by the support and adapted to be operatively engaged with a sound record and to be lifted therefrom by the tiltable support, means for swinging the tone arm outwardly when it is lifted from the sound record, means for adjusting the tone arm relative to the tone arm swinging means for positioning the tone arm to start the playing of a record at any portion of the same, means for tilting the support to lift the tone arm from the record comprising an electric motor device, an electric circuit including the said device, a movable contact associated with the tone arm and movable with the same, a normally stationary contact arranged in the path of the movable contact for closing the said circuit to operate the motor.

ate the electric motor device, and means for holding the circuit closed until the tone arm is returned to its starting position.

11. In mechanism for reproducing and repeating the whole or any selected portion of a sound record, a tiltable support, a sound reproducer including a horizontally swinging tone arm carried by the support and adapted to be operatively engaged with a sound record and to be lifted therefrom by the tiltable support, means for swinging the tone arm outwardly when it is lifted from the sound record, means for adjusting the tone arm relative to the tone arm swinging means for positioning the tone arm to start the playing of a record at any portion of the same, means for tilting the support to lift the tone arm from the record comprising an electric motor device, an electric circuit including the said device, a movable contact associated with the tone arm and movable with the same, a normally stationary contact arranged in the path of the movable contact for closing the said circuit to operate the electric motor device, a mercury switch arranged in parallel with the said contacts for maintaining the circuit closed until the tone arm is returned to its starting position, and means for operating the mercury switch.

12. In mechanism for reproducing and repeating the whole or any selected portion of a sound record, a tiltable support, a sound reproducer including a horizontally swinging tone arm carried by the support and adapted to be operatively engaged with a sound record and to be lifted therefrom by the tiltable support, means for swinging the tone arm outwardly when it is lifted from the sound record, means for adjusting the tone arm relative to the tone arm swinging means for positioning the tone arm to start the playing of a record at any portion of the same, means for tilting the support to lift the tone arm from the record comprising an electric motor device, a cam operatively connected with the motor device and arranged to actuate the tiltable support to lift the tone arm from the record, means actuated by the tilting movement of the support for swinging the tone arm to its starting position when the support is elevated, a motor circuit including a normally stationary contact and a movable contact associated with the tone arm and movable with the same for closing the circuit to lift the tone arm from the record when the selected portion of the same has been played.

13. In mechanism for reproducing and repeating the whole or any selected portion of a sound record, a tiltable support, a sound reproducer including a horizontally swinging tone arm carried by the support and adapted to be operatively engaged with a sound record and to be lifted therefrom by the tiltable support, means for swinging the tone arm outwardly when it is lifted from the sound record, means for adjusting the tone arm relative to the tone arm swinging means for positioning the tone arm to start the playing of a record at any portion of the same, means for tilting the support to lift the tone arm from the record comprising an electric motor device, a cam operatively connected with the motor device and arranged to actuate the tiltable support to lift the tone arm from the record, means actuated by the tilting movement of the support for swinging the tone arm to its starting position when the support is elevated, a motor circuit including a normally stationary contact and a movable contact associated with the tone arm and

movable with the same for closing the circuit to lift the tone arm from the record when the selected portion of the same has been played, a mercury switch in parallel with the said contacts, and means for operating the mercury switch including a spring for moving the mercury switch in one direction and a cam actuated by the motor for moving the mercury switch in the opposite direction.

14. In mechanism for reproducing and repeating the whole or any selected portion of a sound record, including a tilting support, a sound reproducer including a horizontally swinging tone arm carried by the support and adapted to be operatively engaged with a record and to be lifted therefrom by the tilting support, means for tilting the support to lift the tone arm from the record comprising a solenoid having a movable core, spring means connected with the tiltable support and arranged to be placed under tension by the core of the solenoid, means associated with and operated by the tone arm for energizing the solenoid, and means operated by the tilting of the support for swinging the tone arm to return the same to its starting position when the tone arm is lifted from the record.

15. In mechanism for reproducing and repeating the whole or any selected portion of a sound record, including a tilting support, a sound reproducer including a horizontally swinging tone arm carried by the support and adapted to be operatively engaged with a record and to be lifted therefrom by the tilting support, means for tilting the support to lift the tone arm from the record comprising a solenoid having a movable core, a spring connected with the tiltable support and arranged to be placed under tension by the upward movement of the solenoid core, means for controlling the movement of the tiltable support when the same is actuated by said spring, and means operated by the tone arm for energizing the solenoid when the selected portion of the record has been played.

16. In mechanism for reproducing and repeating the whole or any selected portion of a sound record, including a tiltable support, a sound reproducer carried by the tiltable support and including a horizontally swinging tone arm adapted to be operatively engaged with the sound record and to be lifted therefrom by the tilting support, means for tilting the support to lift the tone arm from the sound record including a solenoid, and a spring device arranged to be placed under tension by the solenoid for actuating the tiltable support, means for energizing the solenoid comprising a circuit having a normally stationary contact and provided with a movable contact associated with the tone arm and movable by the same to close the circuit and energize a solenoid, means for swinging the tone arm to return the same to its initial position when the tone arm is lifted from the record, a tiltable mercury switch also movable with the tone arm and arranged in parallel with the said contacts, and means for holding the mercury switch in its closed position until the tone arm is returned to starting position and said contacts have been separated without sparking.

17. In mechanism for reproducing and repeating the whole or any selected portion of a sound record, including a tiltable support, a sound reproducer carried by the tiltable support and including a horizontally swinging tone arm adapted to be operatively engaged with the sound record and to be lifted therefrom by the tilting

support, means for tilting the support to lift the tone arm from the sound record including a solenoid, a spring device arranged to be placed under tension by the solenoid for actuating the tiltable support, means for energizing the solenoid comprising a circuit having a normally stationary contact and provided with a movable contact associated with the tone arm and movable by the same to close the circuit and energize a solenoid, 10 means for swinging the tone arm to return the same to its initial position when the tone arm is lifted from the record, a switch carrying lever also associated with the tone arm and movable with the same, a mercury switch supported by 15 the lever and arranged in parallel with the said contacts, a switch controlling element arranged to be engaged by the said lever when the tone arm is elevated and adapted to hold the lever against movement for maintaining the circuit 20 closed until the tone arm has been returned to its starting position, said lever being carried beyond the switch controlling member at the end of the return movement of the tone arm to permit the mercury switch to open the circuit and deener- 25 gize the solenoid.

18. In mechanism for reproducing and repeating the whole or any selected portion of a sound record, a sound reproducer including a horizontally swinging tone arm adapted for coaction with 30 the sound record, means for controlling the horizontal swinging movement of the tone arm including form gearing connected with the tone arm, a drum for rotating the gearing provided with a spirally graduated peripheral portion having 35 graduations corresponding to the pitch grooves of a sound record, and a transversely slideable indicator associated with the spirally graduated portion of the drum and actuated by the same and cooperating with the graduations thereof.

40 19. In mechanism for reproducing and repeating the whole or any selected portion of a sound record, a sound reproducer including a horizontally swinging tone arm adapted for coaction with the sound record, means for controlling the 45 horizontal swinging movement of the tone arm including worm gearing connected with the tone arm, a drum connected with the gearing and provided in its periphery with a spiral groove defining a spiral peripheral surface provided with 50 graduations corresponding in number with the pitch grooves of a sound record, and a transversely slideable indicator provided with means for engaging the spiral groove and provided with a window having an indicating portion coacting 55 with the graduations.

20. In mechanism for reproducing and repeating the whole or any selected portion of a sound record, a sound reproducer including a horizontally swinging tone arm adapted for coaction 60 with the sound record, means for controlling the swinging movement of the tone arm including a manually operable drum provided at its periphery with a spiral surface having graduations corresponding to the pitch grooves substantially cor- 65 responding in number to the number of the pitch grooves of a sound record, and an indicator cooperating with the spiral surface of the drum and movable transversely of the drum to maintain its coacting position with the graduations of 70 the same when the drum is rotated.

21. In mechanism for reproducing and repeating the whole or any selected portion of a sound record, including a support mounted to tilt on a horizontal axis, a sound reproducer including a 75 horizontally swinging tone arm adapted to be

operatively engaged with a record and to be lifted therefrom by the tilting support, means for tilting the support, lifting the tone arm and for swinging the tone arm to return the same to its starting position, said means including an electric motor device and a circuit having a contact movable with the tone arm and a normally stationary contact arranged to be electrically engaged by the movable contact for closing the circuit to actuate the tiltable support, means for adjusting the tone arm and a movable contact to position the tone arm with relation to the record, means for adjusting the normally stationary contact toward and from the movable contact to control the amount of the sound record to be 15 played, each of said adjusting means being provided with a manually operable drum provided at its periphery with a spiral groove defining a spiral surface provided with graduations corresponding substantially in number to the 20 number of pitch grooves of a sound record, and a transversely slideable indicator provided with means to cooperate with the graduations of the 25 said spiral surface and having means for engaging the groove whereby when the drum is rotated the indicator will be caused to slide transversely of the drum to maintain its indicating means in cooperative relation with the graduations of the said spiral surface.

22. In mechanism for reproducing and repeating the whole or any selected portion of a sound record, including a support tiltable on a horizontal axis and provided with a vertical spindle, a supporting arm loosely arranged on the spindle, a sound reproducer including a tone arm pivoted to the supporting arm, a supporting element mounted on the spindle and means for adjusting the supporting arm and the tone arm with relation to the supporting element comprising a gear having spaced lugs receiving a portion of the supporting arm between them, an adjusting screw mounted on one of the lugs and engaging the supporting arm at one side thereof, and yieldable means mounted on the other lug and engaging the adjacent side of the supporting arm and cooperating with the screw for effecting an adjustment of the supporting arm with relation to the said gear.

23. In mechanism for reproducing and repeating the whole or any selected portion of a sound record, a support mounted for upward and downward movement, a supporting means mounted on the said support for rotative movement, a horizontally swinging tone arm carried by said supporting means, means for adjustably connecting the tone arm to the supporting means to cause the tone arm and the supporting means to swing together, and latching means engageable with the rotative supporting means for limiting the outward swing of the same.

24. In mechanism for reproducing and repeating the whole or any selected portion of a sound record, a support mounted for upward and downward movement, a supporting means mounted on the said support for rotative movement, a horizontally swinging tone arm carried by said supporting means, means for adjustably connecting the tone arm to the supporting means to cause the tone arm and the supporting means to swing together, a second supporting means mounted for rotative adjustment on the said support, and means for moving said support upwardly to lift the tone arm from a sound record and for swinging the first mentioned supporting means outwardly to return the tone arm to its starting 75

position including an electric motor device and a circuit for the same having contacts carried by the said rotative supporting means and adapted to be closed to limit the inward movement of the tone arm and define the amount of a record to be played.

25. In mechanism of the class described, means for rotating a sound record, a sound reproducer having a tone arm with a reproducer stylus, tone arm mechanism for positioning the tone arm with relation to the sound record, an electric contact point attached to the tone arm mechanism to travel with the tone arm when the reproducer stylus is engaged with the record for sound reproduction, a graduated character micrometer drum attached to the tone arm mechanism for manual operation thereof, an indicator operative when the micrometer drum is operated manually by turning to place the tone arm in a relative position above the sound record to the convolution or groove as shown by the indicator on the graduated character drum in register with a graduation or character, a second electric contact point, means for adjusting the second contact point including a second graduated character micrometer drum having the same graduations and characters and indicator as the first micrometer drum and when manually operated places the second electric contact point in advance of the first electric contact point the number of turns of the sound record necessary to complete all or any selected area of the record before the stylus can feed the contact point carried by the tone arm into electrical engagement with the advance micrometer controlled second contact point, and a motor actuated repeat mechanism having a motor circuit including the said electric contact points and adapted to be closed by the movement of the tone arm by the rotation of the sound record which carries the first mentioned contact point into electrical engagement with the second contact point and closes the motor circuit, the graduated characters on both micrometer drums being sufficient to comprehend the sound record grooves.

26. In mechanism for reproducing and repeating the whole or any selected portion of a sound record, a sound reproducer adapted for coaction with a sound record, sound reproducer supporting means mounted for horizontal pivotal movement, means for actuating the record and repeat mechanism including a scale provided with graduations related to the convolutions of the sound record groove, means for selecting on the scale a point related to a convolution of the sound record groove and for adjusting the reproducer with relation to the supporting means, means for returning the supporting means to a definite position and the reproducer to its selected starting position, and means connected with the said means for determining the number of rotations of the sound record permitted by the repeat mechanism.

27. A device of the class described, including a tone arm having a reproducer stylus tone arm supporting means mounted for horizontal pivotal movement, a spiral scale having a plurality of convolutions and provided with graduations related to the convolutions of the groove of a sound record, means for selecting on the scale a point related to a convolution of the sound record groove, and means connected with said means and with the tone arm for adjusting the tone arm with relation to the tone arm supporting means for enabling the reproducer stylus to be placed

in the convolution of the sound record groove related to said selected scale point when the tone arm is lowered to the sound record.

28. In mechanism for reproducing and repeating the whole or any selected portion of a sound record having a sound track, a sound reproducer adapted for coaction with a sound record, sound reproducer supporting means mounted for horizontal pivotal movement, means for actuating the sound record, and repeat mechanism including separate indicating means movable to different positions related to different convolutions of the sound track of the sound record for determining the beginning and end of the material of the sound record to be played and repeated, means for adjusting the sound reproducer with relation to the reproducer supporting means for positioning the reproducer above the convolution on the sound record related to the reference position selected with one of the indicating means, means for lowering the reproducer and stylus to the selected convolution of the sound track of the sound record designated by such indicating means and reference position selected, means connected with the other of such indicating means and operated by the same for determining the end of the number of record convolutions to be played and repeated of the materials related to the reference positions selected by the movable indicating means, and means for returning the reproducer supporting means to a definite position and the reproducer to its selected starting position.

29. In mechanism for reproducing and repeating the whole or any selected portion of a sound record, a sound reproducer adapted for coaction with a sound record, means for actuating the record, a support carrying the reproducer and having means for pivotally mounting the same on a vertical axis and movable downwardly to operatively engage the reproducer with selected portions of the record and upwardly to withdraw the reproducer therefrom, means carried by the support and movable with respect to the same to impart movement to the reproducer to return the reproducer to its starting position when the reproducer is lifted from the record, and means for effecting relative movement between the last mentioned means and the support when the latter is moved upwardly to lift the reproducer from the record.

30. In mechanism for reproducing and repeating the whole or any selected portion of a sound record, a sound reproducer adapted for coaction with a sound record, means for actuating the record, a support carrying the reproducer and having means for pivotally mounting the same on a vertical axis and movable downwardly to operatively engage the reproducer with selected portions of the record and upwardly to withdraw the reproducer therefrom, means for permitting horizontal swinging movement of the reproducer, a member carried by the support and movable with respect to the same to impart movement to the reproducer to return the reproducer to its starting position when the reproducer is lifted from the record, and means for effecting relative movement between the member and the support when the latter is moved upwardly to lift the reproducer from the record.

31. In mechanism for reproducing and repeating the whole or any selected portion of a sound record, a support movable upwardly and downwardly, a bracket element mounted for horizontal pivotal movement on the support, a sound re-

producer adapted for cooperation with a sound record and including a horizontally swinging arm mounted on and movable with the bracket element and adapted to be operatively engaged with the sound record by the downward movement of the support and to be withdrawn therefrom by the upward movement of the support, and means engageable with the bracket element for actuating the same to swing the arm and the sound 5

producer to return the latter to its starting position when the support is moved upward to lift the reproducer from the record.

32. In mechanism for reproducing and repeating the whole or any selected portion of a sound record, a support movable upwardly and downwardly, a sound reproducer including a horizontally swinging arm carried by the support, said sound reproducer being adapted to be operatively engaged with a sound record by the downward movement of the support and to be lifted from the record by the upward movement of the support, means for raising and lowering the support and for swinging the arm to return the reproducer to its starting position comprising an electric motor device, an electric circuit including the said device, a movable contact associated with the horizontally swinging arm and movable with the same, a normally stationary contact arranged in the path of the movable contact for closing said circuit to operate the electric motor device, and means for connecting the movable contact with the tone arm for adjusting the tone arm with relation to the movable contact.

33. In mechanism for reproducing and repeating the whole or any selected portion of a sound record, a support movable upwardly and downwardly, a sound reproducer including a horizontally swinging arm carried by the support, said sound reproducer being adapted to be operatively engaged with a sound record by the downward movement of the support and to be lifted therefrom by the upward movement of the support, means for moving the support upwardly and downwardly and for swinging said arm to return the sound reproducer to its starting position comprising an electric motor device, a motor circuit including a normally stationary contact, a movable contact associated with the horizontally swinging arm and movable with the same for closing the circuit to lift the reproducer from the record when the selected portion of the same has been played, a mercury switch arranged in parallel with said contacts for holding the circuit closed until the reproducer has returned to its starting position, and means for operating the mercury switch including a spring for moving the mercury switch in one direction, and a cam actuated by the motor for moving the mercury switch in the opposite direction.

34. In mechanism for reproducing and repeating the whole or any selected portion of a sound record, a sound reproducer including a horizontally swinging arm and adapted for coaction with the sound record, means for varying the horizontal swinging of the arm including gearing connected with the arm, a drum for rotating the gearing provided with a spirally graduated peripheral portion comprising a plurality of convolutions and having graduations corresponding to the pitch grooves of a sound record and extending around the drum a plurality of times, indicating means associated with the spirally graduated portion of the drum and cooperating with the graduations thereof, and means for

causing the indicating means to move automatically transversely of the drum when the latter is rotated.

35. In mechanism for reproducing and repeating the whole or any selected portion of a sound record including a support provided with a vertical spindle, a supporting arm loosely arranged on the spindle, a sound reproducer including a tone arm pivoted to the supporting arm, and means for adjusting the supporting arm and the tone arm comprising a member having spaced lugs receiving a portion of the supporting arm between them, an adjusting screw mounted on one of the lugs and engaging the supporting arm at one side thereof and yieldable means mounted on the other lug and engaging the adjacent side of the supporting arm and cooperating with the screw for effecting an adjustment of the supporting arm with relation to the said member.

36. In mechanism for reproducing and repeating the whole or any selected portion of a sound record, including means for rotating a sound record, a tone arm, tone arm supporting means mounted for horizontal pivotal movement to permit the swinging of the tone arm, means connected with the tone arm and the supporting means for adjusting the tone arm for positioning the stylus of the tone arm to a relating groove position on the record, an electric contact carried by the supporting means, a second electric contact, means for positioning the second contact the necessary distance in advance of the first contact to repeat the whole or the selected portion of the record, a motor actuated repeat mechanism having a motor circuit including said contacts, and means for returning the tone arm supporting means to a definite position and the tone arm to its selected starting position.

37. In mechanism for reproducing and repeating the whole or any selected portion of a sound record, including means for rotating a sound record, a tone arm, tone arm supporting means mounted for horizontal pivotal movement to permit the swinging of the tone arm, means connected with the tone arm and the supporting means for adjusting the tone arm for positioning the stylus of the tone arm to a relating groove position on the record, means for lifting the tone arm from the record and for returning the tone arm supporting means to a predetermined position and the tone arm to its selected starting position including a motor and a motor circuit having a pair of contacts, one of the contacts being mounted on the tone arm supporting means and movable with the tone arm and carried into electrical engagement with the other contact to close the motor circuit, micrometer means for positioning the other contact the necessary distance in advance of the said movable contact determined by a chart of the sound record content correlated with the micrometer means and with the grooves of the sound record to reproduce and repeat the whole or any portion of the record by the closing of the motor circuit through the feed of the stylus of the tone arm in the groove of the record which moves the movable contact into electrical engagement with the micrometer adjusted contact.

38. In mechanism for reproducing and repeating the whole or any selected portion of a sound record, including means for rotating a sound record, a tone arm, tone arm supporting means mounted for horizontal pivotal movement to permit the swinging of the tone arm, means

for connecting the tone arm with the supporting means for adjusting the tone arm to position the stylus of the tone arm to a relating groove position on the record, repeat mechanism 5 for lifting the tone arm from the record and for returning it to its starting position including a motor and a motor circuit having a pair of contacts, one of the contacts being carried by the tone arm supporting means and being movable 10 with the tone arm and carried by the same into electrical engagement with the other contact to close the motor circuit, micrometer means having graduations correlated with the grooves of the record for positioning the other contact the 15 necessary distance in advance of the movable contact to reproduce and repeat the whole or any portion of the record by the closing of the motor circuit of the repeat mechanism by the feed of the stylus of the tone arm in the groove of the record 20 which moves said movable contact into electrical engagement with the micrometer adjusted contact to effect operation of the repeat mechanism, the distance being determined by a chart of the sound record having numbers or other characters 25 correlated to the graduations of the micrometer means and with the grooves of the sound record.

39. In mechanism for reproducing and repeating the whole or any selected portion of a sound record, a sound reproducer adapted for coaction 30 with a sound record, a support carrying the reproducer and movable upwardly and downwardly to operatively engage the reproducer with selected portions of the record and to withdraw the reproducer therefrom, said reproducer being 35 mounted for horizontal swinging movement on the support, and means for returning the reproducer to its selected starting position including a member movably mounted on the support and means operated by the upward movement of the 40 support to effect relative movement between said member and the support for returning the reproducer to said starting position.

40. In mechanism for reproducing and repeating the whole or any selected portion of a sound record, a support mounted for upward and downward movement only, a sound reproducer adapted 45 for coaction with a sound record and including a tone arm mounted for horizontal pivotal movement on the support and actuated in one direction by engagement of its reproducer stylus with the groove of the record, said tone arm and stylus being carried to and from the record by the downward and upward movement of the support, means for actuating the record, and means for 50 swinging the tone arm in the opposite direction to return the tone arm to its selected starting position including a member movably mounted on the support and means for effecting relative movement of said member and said support during the upward movement of the support to 55 cause the said member to swing the tone arm to its starting position.

41. In mechanism for reproducing and repeating the whole or any selected portion of a sound record, a support tiltable on a horizontal axis, a sound reproducer adapted for coaction with a sound record and carried by the support in the tilting movement thereof to operatively engage the reproducer with the sound record and to lift 60 the reproducer therefrom, said reproducer being mounted for swinging movement with respect to the support, means actuated by the tilting movement of the support for returning the reproducer to its starting position after playing the 65 whole or any portion of the record, and means

operable when the reproducer is returned to its starting position for locking the reproducer against movement independently of the support for retaining the reproducer in its starting position until it is lowered to the record by the 5 support.

42. In mechanism for reproducing and repeating the whole or any selected portion of a sound record, a support, means for mounting the support for upward and downward movement, a sound reproducer including a tone arm pivotally mounted on the support for horizontal swinging movement with respect to the support and adapted to be operatively engaged with a sound record and to be withdrawn therefrom by the 10 upward movement of the support, means actuated through the upward movement of the support for swinging the tone arm horizontally to return the same to its starting position when the tone arm is lifted from the record after playing 15 the whole or any portion of the record, and means for locking the tone arm against swinging movement when the tone arm is returned to its starting position and until the tone arm is 20 reengaged with the record.

43. In mechanism for reproducing and repeating the whole or any selected portion of a sound record, means for rotating a sound record, a pivoted member, a sound reproducer carried by 25 said member, supporting means for said member mounted for horizontal swinging movement, means movable upwardly and downwardly to engage the stylus of the reproducer with the sound record and to lift it therefrom, adjusting 30 means for connecting the pivoted member with the horizontally swinging supporting means and for positioning the stylus of the reproducer to a selected groove of the sound record, means for limiting the swinging movement of said supporting means and means separate from the 35 record for operating said raising and lowering means to lift the sound reproducer from the record and return the horizontally swinging supporting means to a definite position and the reproducer to its selected starting position at a 40 greater speed than that of the reproducer when the same is moved inwardly toward the center of the record by the spiral groove thereof.

44. In mechanism for reproducing and repeating the whole or any selected portion of a sound record, including means for rotating the sound record, a tone arm, tone arm supporting means mounted for horizontal pivotal movement to permit the swinging of the tone arm, means connected with the tone arm and with the supporting means for adjusting the tone arm for positioning the stylus thereof to a relating groove position on the sound record, means for limiting the swinging movement of the tone arm supporting means, and means separate from the 50 record for returning the tone arm supporting means to a definite position and the tone arm to its selected starting position at a greater rate of speed than when the tone arm is moved inwardly toward the center of the sound record by the 55 spiral groove thereof.

45. A device of the class described including a tone arm having a reproducer stylus, a scale provided with graduations related to each of the convolutions of the sound record, a pointer co-operating with said graduations, manually operable means for effecting relative movement between the scale and the pointer for positioning the pointer at a graduation related to any convolution on the sound record, and separate 60

means connected with said means and with the tone arm for actuating the tone arm to move the tone arm at a speed less than said manually operable means to place the reproducer stylus in the groove of the sound record related to said selected scale graduation.

46. A device of the class described including a tone arm having a reproducer stylus, a scale provided with graduations related to each of the convolutions of the sound record, a pointer co-operating with said graduations, manually operable means for effecting relative movement between the scale and the pointer for positioning

the pointer at a graduation related to any convolution on the sound record, separate means connected with said means and with the tone arm for actuating the tone arm to move the tone arm at a speed less than said manually operable means to place the reproducer stylus in the groove of the sound record related to said selected scale graduation, and repeat mechanism for permitting any predetermined number of convolutions of the sound record to be reproduced. 5

ARTHUR L. RUNYAN.

CERTIFICATE OF CORRECTION.

Patent No. 2,081,885.

May 25, 1937.

ARTHUR L. RUNYAN.

It is hereby certified that error appears in the printed specification of the above numbered patent requiring correction as follows: Page 10, first column, line 32, claim 18, for "form" read worm; and that the said Letters Patent should be read with this correction therein that the same may conform to the record of the case in the Patent Office.

Signed and sealed this 24th day of August, A. D. 1937.

means connected with said means and with the tone arm for actuating the tone arm to move the tone arm at a speed less than said manually operable means to place the reproducer stylus in the groove of the sound record related to said selected scale graduation.

46. A device of the class described including a tone arm having a reproducer stylus, a scale provided with graduations related to each of the convolutions of the sound record, a pointer co-operating with said graduations, manually operable means for effecting relative movement between the scale and the pointer for positioning

the pointer at a graduation related to any convolution on the sound record, separate means connected with said means and with the tone arm for actuating the tone arm to move the tone arm at a speed less than said manually operable means to place the reproducer stylus in the groove of the sound record related to said selected scale graduation, and repeat mechanism for permitting any predetermined number of convolutions of the sound record to be reproduced. 5
